THOMAS J. HODGKINS, JR., OF PEEKSKILL, NEW YORK.

Design No. 3,164, dated August 25, 1868.

DESIGN FOR BASE OF A STOVE.

The Schedule referred to in these Letters Patent and making part of the same.

TO ALL WHOM IT MAY CONCERN:

Be it known that I, THOMAS J. HODGKINS, of Peekskill, in the county of Westchester, and State of New York, have invented a new and useful Improvement in Design for Stoves; and I do hereby declare that the following is a full, clear, and exact description thereof, which will enable others skilled in the art to make and use the same, reference being had to the accompanying drawings, forming part of this specification, in which—

The photograph represents a perspective view of the base of a stove.

Similar letters of reference indicate like parts.

This invention relates to a new and original design for the base of a stove.

A is the base, B the register to ash-drawer, and C the flange on which the heat-radiating draught-pipe is fitted.

On the lower part of the base, all around and near its edge, there is a bead, a composed of straight upright flutes, and above the bead a there is an ornament, b, which extends all around the base, but not around the front of the ash-drawer, the ornament b being composed of inverted T-shaped projections.

Above the ornament b there is an ornament composed of upright flutes c, d, and e, the flutes c being quite long or high, d rather shorter than c, and e the shortest of all, three small flutes, e, being between one long one, c, and a flute, d, of the second size. Above this latter ornament there is another precisely similar to the lower one, a.

Having thus described my invention, what I claim as new, and desire to secure by Letters Patent, is—
The design for the base of a stove, as herein shown and described.

The above specification of my invention signed by me this,   day of   , 1868.
